ELECTRON DISCHARGE DEVICE

Joe F. Stephens, Owensboro, Ky., assignor to General Electric Company, a corporation of New York

Application April 29, 1955, Serial No. 504,957

4 Claims. (Cl. 313—261)

My invention relates to electron discharge devices and pertains more particularly to new and improved electrode mounting means for electron discharge devices.

In some electron discharge devices, such as receiving tubes, it is customary to mount the electrode elements thereof between spaced insulators such as mica disks. Usually these electrodes are arranged in closely spaced relationship. This close spacing and the operating characteristics of the tubes are often such as to result in a tendency toward arc-over and inter-electrode leakage across surface portions of the insulators. Generally, it is desirable to minimize any tendency toward arc-over and to minimize any inter-electrode leakage and, broadly considered, the present invention provides means to accomplish these desirable ends.

The primary object of my invention is to provide a new and improved electron discharge device having a high arc-over rating and low inter-electrode leakage.

Another object of my invention is to provide new and improved electrode supporting means for electron discharge devices.

Another object of my invention is to provide in an electron discharge device, a new and improved electrode supporting arrangement adapted for minimizing any tendency toward arc-over in the tube and for minimizing inter-electrode leakage.

Further objects and advantages of my invention will become apparent as the following description proceeds and the features of novelty which characterize my invention will be pointed out with particularity in the claims annexed to and forming part of this specification.

In carrying out the objects of my invention I provide an electron discharge device including an envelope wherein is arranged spaced insulative support assemblies between which are mounted a plurality of electrodes in closely spaced relation. The assemblies each comprise an apertured first insulative member having a slightly conductive coating thereon and a second insulative member secured across the aperture in the first member and having a highly insulative coating. High potential electrodes of the device are mounted between the first insulative members and low potential electrodes are mounted between the second insulative members. The side edges of the second insulative members are spaced from the corresponding edges of the apertures in the first members.

For a better understanding of my invention reference may be had to the accompanying drawing in which:

Fig. 1 is a partially sectionalized elevational view of an electron discharge device illustrating my invention;

Fig. 2 is a sectional view taken along the line 2—2 in Fig. 1 and looking in the direction of the arrows;

Fig. 3 is an exploded perspective view illustrating an insulative support assembly of my invention; and

Fig. 4 is a partially sectionalized elevational view of a modified form of my support assembly.

Referring to the drawing I have shown in Fig. 1 an electron discharge device or tube designated 1 and of

the type generally referred to as a receiving tube. The tube 1 includes an insulative envelope 2 wherein is housed an assembly 3 generally referred to in the art as a tube cage. The tube cage comprises a plurality of electrode elements and mounting means therefor and will be described in more detail hereinafter. Suitably mounted atop the cage is a getter assembly generally designated 4. This assembly may be of any construction well-known in the art and need not be described in detail herein.

5 The tube 1 further includes an insulative base 5 carrying a plurality of prongs 6 suitably electrically connected to conductive leads 7 which extend in a sealed manner through the lower end of the envelope 2 for supporting the cage 3 and making electrical connections with the various electrode elements thereof. Additionally, the base 5 includes a bayonet plug 8 adapted for facilitating insertion and orientation of the prongs 6 in the receptacles of a tube socket (not shown). Suitably mounted on the envelope opposite the base 5 is a conductive top cap 9 adapted for making electrical connection through a conductive lead 9a to an electrode in the cage 3.

10 The cage 3 includes a cathode 10 which may be of the indirectly heated type shown and comprise a sleeve 11 having a suitable electron emissive coating 12 and a

15 heating element or filament 13 therein; or, alternatively, the cathode may be of the directly heated type well-known in the art. The cathode 10 is adapted for being electrically connected by a tab 14 to one of the leads 7 while the ends of the filament 13 are each adapted for

20 being similarly connected to an appropriate one of the leads 7. Further included in the cage structure is a grid 15 comprising a pair of spaced support rods 16, one of which is adapted for being suitably electrically connected to one of the leads 7, and a helically wound grid wire 17.

25 For purposes of simplification of illustration only one grid 15 is shown. However, it will be understood that any desired number of such electrodes could be provided in the illustrated type of tube. Further, it will readily seem that the novel features of my invention can be 30 utilized in other tube types than the single coaxial arrangement shown, as for example multiple-unit tubes such as double diodes, triodes and the like, or combinations thereof.

35 Also included in the particular tube type shown, and perhaps better seen in Fig. 2, is a beam deflection plate 18 which comprises a spaced pair of vertical portions 19 of substantially U-shaped cross section interconnected by a plurality of horizontal portions 20. The beam deflection plate 18 is adapted for being suitably electrically connected to an appropriate pair of the leads 7.

40 Another electrode included in the cage 3 is an anode 21 which may be tubular and of any desired cross-sectional configuration. Additionally, the anode in the illustrated tube type is the electrode adapted for being 45 electrically connected by the above-mentioned leads 9a to the top cap 9. During normal operation of the tube 1, the anode 21 is subject to relatively high peak positive pulse voltages and, therefore, shall be hereinafter referred to as the high potential electrode or element. The

50 cathode 10, grid 15 and beam deflection plate 18 operate at relatively low potentials and shall hereinafter be referred to collectively as the low potential electrodes or elements.

55 It will be clear from the drawing that the various electrodes are coaxially arranged in closely spaced relation and are adapted for being mounted by the extension of end portions thereof through insulative support structures.

60 Now, as mentioned above, the anode 21 is subject to high peak-valued positive voltage pulses during normal tube operation. This operating condition together with

the relative close electrode spacing generally results in a tendency toward arc-over and inter-electrode leakage, especially at surface portion of the electrode support structure.

My invention contemplates the provision of a tube structure including insulative support arrangements or assemblies particularly adapted for minimizing arc-over thereby to increase the arc-over rating of the tube and for minimizing inter-electrode leakage. As seen in Figs. 1-3, I have provided a pair of spaced insulative support assemblies 25, one assembly for the upper cage support and the other for the lower cage support. These assemblies may be identically arranged or, if desired, the orientation of the elements of the assemblies can be reversed, according as the assembly is used for top or bottom cage support, as will appear.

As perhaps best seen in Fig. 3, each assembly 25 includes an insulative first member or disk 26 which may be formed of mica or any suitable insulative material. Additionally, in accordance with common practice, the disks 26 may be further formed to include circumferentially spaced points 27 to facilitate the fitting thereof transversely in the envelope 2 in the manner shown in Figs. 1 and 2. The disk 26 is provided with a coating indicated by 28 in Fig. 3, the substance and purpose of which will be brought out in detail hereinafter.

Provided in the center of each disk 26 is an enlarged aperture 29 which may be hexagonal, as shown, or of any other configuration which provides elongated opposite side edges 30. Outwardly spaced from the side edges 30 are apertures 31 adapted for receiving tabs 32 formed off oppositely extending lateral extensions of the anode 21. Thus, the disks 26 are adapted for having the relatively high potential element or anode 21 mounted therebetween in the manner shown in Fig. 1.

Provided for being secured across the apertures 29 of the disks 26 in the manner shown in Figs. 1 and 2, as by the use of eyelets 33 or any suitable securing means, is an elongated insulative second member or strip 34. The strip 34 is provided with a coating, indicated by 35 in Fig. 3, the substance and purpose of which will also be brought out in detail hereinafter. The strip 34 may also be formed of mica or any suitable insulative material and is narrower in width than the distance between the edges 30 of the aperture 29 in the disk 26. The relative dimensioning of the strip 34 and the aperture 29 results in the provision of elongated spaces or openings, designated 36 in Fig. 2, on either side of the strip, the purpose for which will be brought out in detail hereinafter.

Additionally, the strips 34 are each formed to include a central elongated aperture 37 for receiving an end of the cathode 10, a spaced pair of apertures 38 for receiving end portions of the grid rods 16, and a second pair of spaced apertures 39 for receiving tabs 40 formed off the beam deflection plate 18. As seen in Fig. 1, the tabs 40 on the lower portion of the plate 18 are adapted for extending through the apertures 39 and for being suitably electrically connected, as by welding, to a shield member 41 which in turn is similarly connected to a pair of the leads 7. Thus, is provided the above-referred-to electrical connection between the plate 18 and the appropriate ones of the leads 7. In the just-described manner the strips 34 of the top and bottom support assemblies are adapted for having the relatively low potential elements, or elements other than the anode 21, mounted coaxially therebetween.

The arrangement described above results in minimizing the probability of arc-over between the relatively high and low-potential elements whereby a high arc-over rating for the tube 1 can be assigned and further, minimizes any inter-electrode leakage between the low potential elements. The high arc-over rating thus obtained is due in part to the mounting of the high and low potential elements in separate insulative members located in different planes which results in physical and

electrical isolation of the high potential element with respect to the low potential elements and the abrupt discontinuity or interruption of the surface of the insulation between the high and low potential elements.

5 The high arc-over rating is further due to the above-referred-to coating 28 on the disks 26. The coating 28 is formed of any material and to a thickness which will adapt it for being slightly conductive at the relatively high peak positive voltage pulses to which the high 10 potential element of the tube is subjected during normal operation. The coating 28 is effective for minimizing the tendency toward arc-over or increasing the arc-over rating inasmuch as it affords the anode potential a high resistance leakage path which allows the 15 potential to be distributed over the entire areas of the disks 26, thereby to prevent the buildup or accumulation of any electric charge of arcing magnitude on any single portion of the disks. I have found sodium silicate and potassium silicate to be suitable materials for forming the coating 28. These materials have been found 20 particularly suitable since, in addition to being slightly conductive at the relatively high potentials, they require no binders, they have surface textures which particularly adapt them for use as coating materials, and they 25 do not tend to poison or affect deleteriously oxide coated cathodes. It is to be understood, however, that my invention is not limited to the use of the above enumerated materials. Any type of coating may be used which will present a slightly conductive or very 30 high resistivity conduction path to the flow of electric current between the high and low potential elements.

Still further, the tendency toward arc-over at the electrode support assemblies 25 is minimized by the 35 particular configurations of the disks 26 and strips 34 comprising the support assemblies.

As seen in Fig. 4 the arc path over each of the assemblies 25 and, therefore, the arc-over rating of the tube, may be further increased by spacing the disks 26 and their 40 respective strips 34. This may be suitably accomplished by the use of elongated eyelets 42 having suitable insulative spacers 43 fitted thereon and disposed between the disks 26 and the strips 34.

The inter-electrode leakage between the low potential 45 electrodes or elements is minimized by the above-referred-to coating 35 on the strips 34. The coating 35 is formed of any material and to a thickness which will adapt it for being highly insulative or resistive to the relatively low potential currents tending to flow between the electrodes in the strips 34 across the surface portions of the strips. Materials which are suitable for forming the coating 35 are aluminum oxide, magnesium oxide, and zirconium oxide. These materials, in addition to being highly resistive to current flow between the relatively 50 low potential elements mounted between the strips 34, are particularly suitable inasmuch as the surface textures and adherence properties thereof particularly adapt them for use as coating materials, and they also do not tend to poison oxide coated cathodes. It is to be understood that this feature of my invention also is not 55 to be limited to the enumerated coating materials. Any type of coating material may be used on the strips 34 which will be highly insulative or resistive to the flow of electric current between the relatively low potential electrodes.

60 Thus it will be seen that I have provided an electron discharge device adapted for having a high arc-over rating and minimal inter-electrode leakage. Additionally, I have provided electrode supporting means which is 65 adapted for increasing the arc-over rating of a tube and minimizing inter-electrode leakage and is particularly adapted for manufacture through use of mass production techniques.

For example, the mica disks 26 may be drum-sprayed 70 or otherwise coated in volume with a solution including

any of the above-referred-to slightly conductive materials. As mentioned above no binder is required with these materials. Similarly the strips 34 may be sprayed with a solution including a highly insulative material. Preferably a suitable binder such as gum arabic or nitro cellulose is used with these latter materials. Thereafter, these elements may all be oven baked to dry them and remove any traces of any coating material binders thereby to leave the elements suitably coated with the desired materials. From the baking oven the coated elements may go to an assembly station whereat they are fastened or secured together as by use of the eyelets 33 or 42 and in the manners shown in the drawing.

While I have shown and described specific forms of my invention, I do not desire my invention to be limited to the particular forms shown and described and I intend by the appended claims to cover all modifications within the spirit and scope of my invention.

What I claim as new and desire to secure by Letters Patent of the United States is:

1. In an electron discharge device including an evacuated envelope and a plurality of electrode elements coaxially arranged in said envelope and including at least one adapted for high potential operation, means for supporting said electrode elements in said envelope and adapted for minimizing arc-over between said elements comprising; an insulative disk having an elongated aperture and an insulative strip carried by said disk, said strip being narrower than said aperture and extending longitudinally across the middle of said aperture whereby laterally extending elongated slots are provided in said support means on either side of said strip, said disk being further apertured for having portions of the high potential element extend therethrough at points laterally disposed relative to said strip and slots, said strip being apertured for having portions of the other of said elements extending therethrough, and a coating of material selected from the group consisting of sodium silicate and potassium silicate on said disk providing a high resistivity conduction path effective for distributing any electrical charges on said disk.

2. In an electron discharge device including an evacuated envelope and a plurality of electrode elements coaxially arranged in said envelope and including at least one adapted for high potential operation, means for supporting said electrode elements in said envelope and adapted for minimizing arc-over between said electrodes and any inter-electrode leakage comprising; an insulative disk having an elongated aperture, and an insulative strip carried by said disk, said strip being narrower than said aperture and extending longitudinally across the middle of said aperture whereby laterally extending slots are provided in said support means on either side of said strip, said disk being further apertured for having portions of the high potential element extend therethrough at points laterally disposed relative to said strip and slots, said strip being apertured for having portions of the other of said elements extending therethrough and a coating of material selected from the group consisting of aluminum oxide, magnesium oxide and zirconium

oxide on said strip adapted for resisting any current flow across said strip.

3. In an electron discharge device including an evacuated envelope and a plurality of electrode elements coaxially arranged in said envelope and including at least one adapted for high potential operation, means for supporting said electrode elements in said envelope and adapted for minimizing arc-over between said elements and minimizing any inter-electrode leakage comprising; an insulative disk having an elongated aperture and an insulative strip carried by said disk, said strip being narrower than said aperture and extending longitudinally across the middle of said aperture whereby laterally extending slots are provided in said support means on either side of said strip, said disk being further apertured for having portions of the high potential element extend therethrough at points laterally disposed relative to said strip and slots, said strip being apertured for having portions of the other of said elements extending therethrough, a coating of material selected from the group consisting of sodium silicate and potassium silicate on said disk providing a high resistivity conduction path effective for distributing any electrical charges on said disk, and a coating of material selected from the group consisting of aluminum oxide, magnesium oxide and zirconium oxide on said strip adapted for resisting any current flow across said strip.

4. In an electron discharge device including an evacuated envelope and a plurality of electrode elements mounted in said envelope and including at least one adapted for high potential operation, means for supporting said electrode elements in said envelope and adapted for minimizing arc-over between said elements comprising; an insulative disk having an enlarged, elongated aperture, an insulative strip carried by said disk, said strip being narrower than said aperture and extending longitudinally across said aperture, thereby to provide laterally extending spaces between the side edges of said strip and the corresponding side edges of said aperture, said disk being further apertured outwardly of said spaces for having the high potential element extend therethrough at points laterally separated from said strip by said spaces, said strip being apertured for having the other electrode elements extend therethrough, said disk having a coating of high-resistivity conductive material effective for distributing any electrical charges on said disk, and said strip having a coating of highly insulative material effective for resisting any current flow across said strip.
